Attorney.

UNITED STATES PATENT OFFICE

JACOB STIRISS, OF NEW YORK, N. Y.

MATCH CARD AND COVER

Application filed May 31, 1927. Serial No. 195,354.

This invention relates to matches, and more especially to match cards and books, and the object of said invention is to protect the matches from ignition while in the card, to so construct and arrange each individual match that it is separate and easily detached by the party using same, to construct and join the card and its cover without the use of metal parts and to so make the card and 10 the cover that they may be readily cut and separated.

These and other objects and details of the invention are more fully described in the following specification, set forth in the claims 15 and illustrated in the accompanying drawings, wherein:

Figure 1 is a perspective view of the improved match card and book when opened.

Fig. 2 is a perspective view of the same 20 closed.

Fig. 3 is a side elevation, closed.

Fig. 4 shows the card blank and the various stages in the making of the matches.

Fig. 5 shows the blank of the cover before 25 being cut up.

A serious objection to the use of match cards is the possibility of one or more of the matches being ignited when not desired, such often occurring in the pocket of the owner 30 and in consequence of friction of one match head with the other, or frequently when a match is struck, the others may be accidentally ignited, destroying the whole card.

In order that the matches may be protected 35 from such occurrences, the improved card 10 is cut from a continuous strip of heavy paper shown in Fig. 4, having slots 11 at a central point and having integral hinges at each side thereof to assist in folding same and preventing 40 too much rigidity when it is attached to the cover 12 at the fold 13.

The matches 14 are cut from each side of 45 the paper strip, and each match is given a ninety-degree twist so that while the middle part of the card lies flat and parallel with the cover, the matches are turned to a right angle to the cover with one edge outward. In consequence of this arrangement the match 50 is weakened at the twist so as to render separation from the card easier and each match

head is separated from the other so that friction is impossible; and, lastly: this arrangement makes each match accessible so it may be easily grasped and detached.

The twisted part 15 may leave a match of 55 sufficient length for practical use and may be at a point between the joint 13 and match head to allow for the burning properties of said match, a quick burning match being necessarily longer.

To further protect the match against the danger of ignition, the cover 12 has tapered ends 16 formed by the indents 17 in the original blank, and these ends are stiffened by means of shellac or varnish and bent into a 60 hood 18 to protect and partly enclose the match head, but which at the same time readily allow the match to be drawn out and separated.

As shown in Fig. 5, the cover strip is divided 70 along the dotted line 19 and between opposite indents 17 while the match card is divided on dotted lines 20 between the slots 11.

The device is completed by applying the 75 abrasive igniting material 21 at the sides of the fold 13 so that in igniting the match it is not only outside of the cover but the remaining matches are protected by the hood 18 and the closed cover. The paste used to attach the 80 card and cover is also a stiffener to retain the parts in the position of Figs. 2 and 3.

By the above construction and with practically 85 no addition of material to similar match cards now in use a maximum of protection is given the match against accidents and destruction.

It is obvious that the parts may be otherwise arranged and modified without departing 90 from the essential features above shown or from the scope of the appended claims.

The indents 17 in the original card strip serve eventually as guide points on which to cut the covers and serve on the latter as well 95 as bevelled corners obviating the sharp point that a square cut would form. The bevel also gives a symmetrical effect to the whole book and leaves no sharp corners to wear and fray while in use.

What I claim as new is:

1. In match cards, a card cut into matches at its edge, said matches being twisted so as to have their original outer faces to oppose each other and to have their heads separated.
2. In match cards, the combination of a card cut into matches at opposite edges, said matches being twisted so that they are separated instead of abutting each other and the card folded to have the cut edges opposite each other but adapted to be separated and protected by enveloping hoods.

10 In testimony whereof I hereunto affix my signature.

15

JACOB STIRISS.
